(57) CLAIM

The ornamental design for the bath soap and dispenser, as described and shown.

DESCRIPTION

FIG. 1 is a perspective see-through view of the bath soap and dispenser showing my new design with the top hinged lid of the housing in an open position and the bar soap contained therein;

FIG. 2 is a front side elevation thereof, showing the dispenser with a closed lid;

FIG. 3 is a rear side elevation thereof;

FIG. 4 is a right side elevation thereof;

FIG. 5 is a left side elevation thereof;

FIG. 6 is a top plan view thereof; and,

FIG. 7 is a bottom plan view thereof.
